UNITED STATES PATENT OFFICE.

WILLIAM H. MADDOX, OF EAST ST. LOUIS, ILLINOIS.

EMERGENCY ANGLE-COCK.

No. 824,036.

Specification of Letters Patent.

Patented June 19, 1906.

Application filed August 7, 1905. Serial No. 273,119.

To all whom it may concern:

Be it known that I, WILLIAM H. MADDOX, a citizen of the United States, and a resident of East St. Louis, St. Clair county, Illinois, have invented certain new and useful Improvements in Emergency Angle-Cocks, of which the following is a specification containing a full, clear, and exact description, reference being had to the accompanying drawings, forming a part hereof.

My invention relates to an emergency angle-cock which is particularly adapted for use whenever the section of the train-pipe of an air-brake system breaks off close to the angle-cock, which breaking of the train-pipe renders the brake system inoperative.

It very often happens that when a train is in operation the metallic train-pipe breaks at a point adjacent the angle-cock carried by the hose, and when this break takes place it is necessary to take the car on which the broken train-pipe is located into the shops for repair; and it is the object of my invention to provide an emergency-cock that can be readily applied to the train-pipe when such a break takes place, thus maintaining the regular service of the brake mechanism and making a temporary repair that is in every way satisfactory until the car can be taken to the shops where the broken train-pipe can be renewed.

To the above purposes my invention consists in certain new and novel features of construction and arrangement of parts, in which—

Figure 1 is an elevation of a portion of the train-pipe, showing an angle-cock connected thereto, a portion of the hose, and a dotted line xx , indicating the point where the break generally occurs in the train-pipe. Fig. 2 is a side elevation of my improved emergency angle-cock applied for use. Fig. 3 is an enlarged detail section taken approximately on the line 3 3 of Fig. 2. Fig. 4 is an enlarged vertical section taken on the line 4 4 of Fig. 2. Fig. 5 is a vertical section taken on the line 5 5 of Fig. 4.

Referring by numerals to the accompanying drawings, 1 indicates the usual metallic train-pipe, which is threaded, as indicated by 2, to receive the usual angle-cock 3, that is detachably secured to the hose 4.

The parts just described are of ordinary well-known construction, and, as heretofore stated, the train-pipe very often breaks at

the point xx or where it joins with the angle-cock.

My improved emergency angle-cock comprises a short section of metallic pipe 5, to one end of which is securely held, by means of a clamp 6, a short piece of hose 7 or analogous flexible pipe, which is of such a size as that it may be fitted onto the end of the train-pipe 1 when the same is broken. Detachably secured to the opposite end of the pipe 5 is an elbow 8, the outer lower end of which is internally screw-threaded and adapted to receive the screw-threaded nipple 9, that is carried by the end of the hose 4 and which is normally seated in the angle-cock 3.

The clamp for securing the flexible hose-section 7 to the train-pipe 1 comprises a loop 10, with which is formed integral a screw-threaded shank 11. Operating in this loop is a clamping member 12, the forward end of which is bifurcated, as indicated by 13, and the end of said member extends downwardly through the lower portion of the loop 10, and its lower end is provided with a slot 14, through which passes a pin 15, the ends thereof being seated in the loop 10. The stem of the member 12 is provided on its opposite sides with shoulders 16, and a sleeve 17 is mounted on the shank 11, the upper end of which sleeve bears against these shoulders 16. A combined nut and lever in the form of a straight bar 18 operates on the screw-threaded end of the shank 11 and when tightened thereon engages against the lower end of the sleeve 17 and forces the same upwardly on the shank 11. When a break occurs in the train-pipe 1, a trainman after detaching the ordinary angle-cock 3 from the nipple 9, carried by the end of the hose 4, screws the free end of the elbow 8 onto said nipple 9, after which the free end of the short hose-section 7 is slipped onto the broken end of the train-pipe 1. The clamp comprises the loop 10 and parts carried thereby, having previously been slipped onto the hose-section 7. 100

When the various parts are so arranged, the loop 10 is moved toward the outer end of the hose-section 7 until it encircles the end of the train-pipe 1, and the operator now manipulates the bar 18 on the screw-threaded end of the shank 11, so as to move the sleeve 17 upwardly onto the shank of the loop and in turn move the clamping member 12 upwardly, so that the bifurcated upper end thereof very tightly engages and clamps upon the hose 7. 110

- This action necessarily draws the loop 10 toward the bifurcated end of the clamping member, and thus the hose is very tightly engaged upon the broken end of the train-pipe. The 5 break is thus temporarily repaired, and the service of the air-brake system is maintained to the end of the run of the train, when the car having the broken train-pipe can be taken into the shops for permanent repairs.
- 10 An emergency angle-cock of my improved construction is simple, strong, and durable, can be readily applied for use, is composed of a minimum number of parts, and can be applied by any person without the use of special tools.
- 15 I claim—

1. The combination with the train-pipe and train-hose of an air-brake system, of a tubular connection detachably fitted to the 20 train-hose, a tubular connection detachably secured to the first-mentioned tubular connection, and an adjustable clamp for securing the second tubular connection to the train-pipe; substantially as specified.

2. An emergency angle-cock, comprising a 25 tubular section adapted to be fitted onto the train-hose of an air-brake system, a tubular section detachably secured to the first-mentioned tubular section, and an adjustable clamp for securing the end of the second tubular section to the train-pipe of the air-brake system; substantially as specified.

3. The combination with the train-pipe and train-hose of an air-brake system, of a 35 tubular connection detachably fitted to the train-hose, a flexible tubular section detachably secured to the first-mentioned tubular connection, and an adjustable clamp arranged to secure the end of the flexible section to the broken end of the train-pipe; substantially as specified.

In testimony whereof I have signed my name to this specification in presence of two subscribing witnesses.

WILLIAM H. MADDOX.
